UNITED STATES PATENT OFFICE

2,260,595

AUTOMOBILE HEATER AND DEFROSTER

Carl H. Will, Winnetka, and Henry W. Fink, Chicago, Ill., assignors to Tropic-Aire, Incorporated, Chicago, Ill., a corporation of Delaware

Original application April 19, 1937, Serial No. 137,842. Divided and this application February 25, 1939, Serial No. 258,412

6 Claims. (Cl. 257—137)

This invention relates to improvements in combined automobile heaters and defrosters, and has for its general object the production of a device of this character in which the structural elements and their functional relationship are such as to provide a more effective device than those heretofore produced for this purpose and which at the same time is cheaper to make and more easily installed. The application is a division of our pending application Serial No. 137,842, filed April 10, 1937, for Automobile heater and defroster.

One of the objects of our invention is to provide such a combined automobile heater and defroster in which the parts are so constructed and arranged that the overall depth of the assembly is not materially increased. This is important in view of the limited space for mounting heaters on the dash of automobiles of current body design.

Another object of our invention is to produce a device of the general character described, in which, as compared with prior devices, a greater volume of heated air for defrosting purposes is delivered without affecting the efficiency of the heater in delivering warm air to the interior of the vehicle.

Still another object of the invention is to provide a device of the character described, in which the air impeller for defrosting purposes is of greater diameter than the pressure fan and may therefore be operated at a lower R. P. M. without sacrificing volume of air delivered for defrosting, at the same time eliminating objectionable noise common to the types of air impellers now used for this purpose.

A further object of our invention is to provide a device of the character described, in which a conventional type of motor having a single shaft may be used and in which the air impellers for heating and defrosting are mounted upon the same shaft.

A further object of the invention is to provide a device of the character described, in which it is not necessary to construct special conduits or casings connecting the heating element or radiator with the casing for the defrosting air impeller, thus providing a more compact structure.

Other objects of the invention will be more fully brought out and will more clearly appear as the description of the invention proceeds.

In order to illustrate our invention in a practical form in which it may be embodied, we have appended hereto a drawing showing a practical construction. It is to be understood, however, that this drawing is illustrative merely and that it is not intended to limit our invention to the details disclosed therein because it will be obvious to those skilled in the art that the details of construction may be varied without sacrificing any of the advantages of the invention and

without departing from the scope thereof, as defined in the appended claims.

In the drawing:

Figure 1 is a vertical section of the heater on a plane parallel with the axis of rotation of the motor shaft; and

Figure 2 is a fragmentary schematic view showing our combined heater and defroster installed in an automobile.

Generally speaking, the heater that we have chosen to illustrate as embodying our invention is of the so-called hot water type, which is to say, that the heating medium is hot water from the engine cooling system. Such a heater is now well known and has been for some years and is practically the only commercially available automobile heater at the present time.

However, it will be clear that the invention may be embodied in other heaters in which the heating medium may be derived from other sources. For example, the heater may be of the exhaust gas type when properly constructed to provide for the effective circulation of air; or, the heater may be a so-called self-contained unit in which the source of heat and the heating medium are not supplied from the engine; or, the heater may derive its heat from steam or hot air. In short, as will more clearly appear as the description proceeds, the construction of the heater itself is not important to our invention except insofar as the construction thereof cooperates with the novel elements of our combination to produce our new and useful device.

Referring now to the drawing. The front section of the shroud or outer casing is designated by the reference character 10 and this shroud has a substantially centrally located opening 11 controlled by suitable deflectors or shutters 12. It will be understood, of course, that the number of deflectors or shutters is immaterial; it is only necessary that they be so arranged and mounted that they will substantially close off the central opening 11 when the delivery of heat is not desired, and so that they may be opened and adjusted to various angular positions to vary the volume of and direct the flow of air to any desired part of the vehicle. In this particular embodiment the deflectors 12 are also rotatably adjustable by manipulation of a suitable knob or handle 13. The radiator structure is generally indicated by the numeral 15. The rear shroud of the outer casing is indicated at 16 and the heater is suitably supported on the dash of an automobile, as by bolts 16'.

The arrangement of the pressure fan and centrifugal blower are best shown in Figure 1. The heater includes a radiator structure or core 15 comprising headers 17 connected by a plurality of tubes 18 upon which are arranged a multiplicity of fins 19. By this means air passages are

formed. Inlet and outlet pipes 20 are provided, permitting ingress and egress of the (in this case liquid) heating medium to and from the headers 17. It will thus be seen that the heater itself is of quite conventional construction.

Assuming that the heating medium is hot water from the engine cooling system, such water enters from one of the pipes 20 into one of the headers 17, whence it passes into the tubes 18, into the other header 17 and out through the other pipe 20.

Means is provided for producing a forced circulation of air through the spaces or air passages between the fins 19 and around the tubes 18, as indicated by the arrows pointing to the left in Figure 1.

In this device there is embodied the principle of a relatively large diameter blower operating in a casing mounted in close proximity to the radiator core so as to draw air therethrough without the necessity for special conduits or ducts.

The motor 23 is located in the center of the radiator core, in a suitable chamber formed therein, and a pressure fan 41 is mounted on one end of motor shaft 42, which end projects rearwardly from the core (as seen from the driver's seat). The shaft of the motor projects forwardly as at 43 and has mounted thereon a centrifugal blower designated 44, which is provided with spider arms 45. These arms 45 are shaped generally like the fan blades of the pressure fan 41, except that they are shown narrower. There is no intention to be limited to their width, however, or to their supporting function. These arms are in a direct path of travel of the air from the pressure fan 41. They may perform the double function of offering no impedance to the flow of air outwardly from the center of the radiator core and of supplementing the forcing action of the fan 44, or both, or may take the place of that fan. The preferred construction, however, is shown in which the fan 41 is used and the elements 45 are narrow and act rather to offer no impedance to the flow of air outwardly, than as means in substitution of the fan 41. It is, however, understood that these various functions alone and in combination are claimed.

The centrifugal blower 44 is provided with blades or vanes 46, which move the air centrifugally. The centrifugal blower 44 operates in the peripheral chamber of the casing 47, which casing is suitably mounted closely adjacent the front of the radiator core and preferably by means which makes said casing removable as well as rotatably adjustable.

A rotatable annulus or shroud 48 is carried by and rotates with the centrifugal blower. In fact, the ring supports the blower. This ring cooperates with a stationary ring 49 to confine and guide the flow of air from the pressure fan 41, and also provides an inner wall for the peripheral fan chamber of the casing 47 of the centrifugal blower.

The casing 47 cooperates with ring 49 to form a spiral chamber which communicates with an auxiliary outlet port or pipe 51. This pipe may be provided with one or more branches 32, as shown in Figure 2. To each branch may be connected a suitable hose 53 leading to a nozzle 54, which is placed close to the windshield 52 of the automobile 51, so that warm air from the blower will pass from said nozzles 54 to be impelled against the windshield, as shown for example in our copending application Serial No.

101,097, filed September 16, 1936. The provision of two branches 32 in Y formation, as shown in Figure 2, permits the attachment of two hoses leading to separate sections of the windshield.

5 The casing 47 is preferably removably adjustably supported, as heretofore mentioned. By this arrangement the said casing may be rotated on the heater so that its chamber delivers to the outlet pipe 31, which should point in the same direction (usually toward the driver), whether the heater be mounted vertically or horizontally upon the dash. The structure 31 also contains valves or dampers, not shown, for controlling the passage of air respectively to the floor to warm the feet of the driver, and to the branches 32 for the windshield.

For safety we provide a screen or grill 50 suitably supported in front of the spider arms or fan blades 45 of the centrifugal blower. This screen or grill is of sufficiently open construction as to offer as little obstruction as possible to the flow of air from the pressure fan 41, or from the fan-like spider arms 45, when they act alone or as supplementary to fan 41.

20 In this specific form of the invention we have achieved compactness necessary for convenient and successful installation in automobiles of modern body design. The casing for the centrifugal blower is close to the radiator core so that the blower is substantially in alignment with that section of the core through which air is drawn for defrosting purposes, and this is accomplished without the necessity of specially formed ducts or conduits. The heat losses incident to transfer of heat from the heater to the blower are also reduced to a minimum.

25 It is to be noted that the fan and blower operate to impell air through the core in the same direction. The blower is of a diameter equal to or slightly greater than the diameter of the pressure fan 41 and of the fan arms 45. Thus the blower may operate at a lower R. P. M. for a desired pressure, with corresponding diminution of noise, an important feature. The centrifugal blower 44 and its casing 47 may be removed from the front of the radiator core if the defrosting attachment is not desired, thus converting the heater to one of conventional form. This removability is a feature of the invention. It is noted that the casing 47 is attached to a ring 47', which ring is in turn attached to the front of the radiator. To the ring 47' the shroud 49 is connected by a plurality of narrow elements 49' and in a manner not to obstruct the intake opening for the peripheral blower chamber.

30 From the foregoing description it will be clear that we have provided a combined automobile heater and defroster of unusual efficiency and compactness. It is understood, of course, that some of the structural details may be changed without sacrificing the advantages pointed out. It is understood that we do not entirely confine ourselves to all of the particular details illustrated and described, although these are claimed.

35 We have illustrated an electric motor but it will be understood that any other type of motor may be used, such, for example, as an air motor operated by the vacuum from the intake manifold of the engine. The motor may be supported by any suitable means such as brackets 23' and preferably has some cushioning means such as is indicated at 24' to reduce transmission of vibration.

40 A casing 25 may be made integral with the rear shroud 16 or separate therefrom, as desired.

It will be noted that the blades 41 of the pressure fan are located quite close to the radiator so that the overall depth of the heater is no greater than that of conventional heaters now on the market. Yet within this depth there is provided a separate air impeller or blower for delivering air for defrosting and this is also located within the confines of the casing 25.

It will be noted that the internal diameter of the impeller 46 is substantially equal to the external diameter of the elements or spider arms 45 and the blades 41. The impeller 46 may be said to surround the elements 45. The elements 45 are struck from or made in one piece with the ring 48, and the elements 46 are struck from or made in one piece with the element 44, which is secured, in this case, by rivets to the element 48. It is conceivable that these elements 45, 48, 44, and 46 may be formed in one piece.

The stationary ring 49 serves to keep the air stream separate and the ring 48 is substantially of the same diameter as the ring 49. It is noted that the screen 50 is supported, not by a ring, but by separate elements 50', attached to the casing 47.

It is again noted that in this form of the invention the air all passes in one and the same direction through the radiator for the two purposes, respectively, for general delivery to the automobile, and for delivery for defrosting. Thus the two air streams are heated by different portions of the same radiator core while passing simultaneously therethrough in the same direction. It is unnecessary in this instance to provide separate sets of ducts within the radiator to direct the flow of air therethrough. Thus no special modification of the conventional radiator is necessary.

It is well known that the pressure created by a centrifugal fan or blower is proportional to the square of its peripheral speed. Hence, with a blower of relatively large diameter, as has been herein provided, the peripheral speed required for a given pressure can be obtained at a low R. P. M. with corresponding diminution of noise. Maximum quietness with adequate air delivery simultaneously for two purposes is an important feature.

The blower casing and its fan or spider arms 45 may be removed, leaving the fan 44, and thus there is provided a universal construction which may be easily converted from a combined heater and defroster into a simple heater of conventional design.

We claim as our invention:

1. In a combined heater and defroster, a heating radiator having air passages, first air-forcing means at one side of the radiator for forcing air through certain of said passages, and second air-forcing means at the opposite side of said radiator for drawing air through other of said passages, the second air-forcing means having an internal diameter as great as the external diameter of the first air-forcing means and having associated therewith air-moving means which supplements the action of said first air-moving means.

2. In a combined heater and defroster, a heating radiator having air passages, first air-forcing means at one side of the radiator for forcing air through certain of said passages, and second air-forcing means at the opposite side of said radiator for drawing air through other of said

passages and having air-moving means which supplements the action of said first air-moving means, and means outside of the radiator for preventing interference between the respective air streams created by said impellers.

3. In a combined heater and defroster, a first casing having main and auxiliary discharge openings, a heating radiator having air passages, air-forcing means arranged between the radiator and the main opening and comprising a second casing having a peripheral chamber discharging into said auxiliary opening, air separating means within the second casing defining the inner wall of said peripheral chamber and acting to guide air from the radiator into said peripheral chamber and to the main outlet opening, an annulus rotative within said last mentioned means and having thereon a centrifugal blower operating in the said peripheral chamber to force air tangentially through said auxiliary opening, a hub, and spider arms connecting the hub with said annulus, said arms being adapted to draw air through said radiator, and means for rotating the hub.

4. In a combined heater and defroster, a first casing having main and auxiliary discharge openings, a heating radiator having air passages, air-forcing means arranged between the radiator and the main opening and comprising a second casing removably attached to the radiator, said second casing having a peripheral chamber discharging into said auxiliary opening, air-separating means within the second casing defining the inner wall of said peripheral chamber and acting to guide air from the radiator into said peripheral chamber and from the radiator to the main outlet opening, an annulus rotative within said last mentioned means and having thereon a centrifugal blower operating in the said peripheral chamber to force air tangentially through said auxiliary opening, means rotating said annulus, and a second air-forcing means at the opposite side of the radiator operated by said rotating means and adapted to draw air through said radiator and out of said main discharge opening.

5. In a combined heater and defroster, a heating radiator having air passages, a fan of the axial delivery type arranged at one side of the radiator for forcing air through a relatively large number of radiator openings for general delivery, and a fan of the centrifugal delivery type at the opposite side of the radiator, receiving air through a much smaller number of passages of said radiator and delivering it centrifugally for defrosting, said fans being mounted on a common shaft which passes through the radiator, and means for driving said shaft.

6. In a combined heater and defroster, a heating radiator having air passages, a fan of the axial delivery type at one side of and forcing air through the radiator, a casing at the opposite side of the radiator providing an opening through which said axially forced air travels to the delivery point, said casing having a fan chamber surrounding it, a fan of the centrifugal delivery type operating in said chamber, said chamber having an intake opening receiving heated air from said radiator and having a delivery opening through which said fan centrifugally delivers the heated air for defrosting, and means for driving said fans.
